UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

FASTENER SUPPLYING AND DELIVERING MECHANISM.

1,076,280.

Specification of Letters Patent.

Patented Oct. 21, 1913.

Original application filed June 23, 1909, Serial No. 503,781. Divided and this application filed July 23, 1910. Serial No. 573,420.

To all whom it may concern:

Be it known that I, GEORGE GODDU, a citizen of the United States, residing at Winchester, in the county of Middlesex and State of Massachusetts, have invented certain Improvements in Fastener Supplying and Delivering Mechanism, of which the following description, in connection with the accompanying drawings, is a specification, like reference characters on the drawings indicating like parts in the several figures.

This invention relates to a fastener supplying and delivering mechanism for machines for inserting fasteners in two superimposed sheets of material, such, for instance, as the quarters of boots and shoes and more particularly to machines for setting lacing hooks or studs although the invention, in its various features, is not limited to setting this particular form of fastener.

The invention is shown as applied to the machine for inserting fasteners, illustrated and described in the inventor's co-pending application, Serial No. 503,781, filed June 23, 1909, from which the present application has been divided, but the present invention is not limited in its use to the particular type of machine illustrated in said co-pending application.

One object of the invention is to provide improved means for mounting the hopper, for holding fasteners to be supplied to the setting dies, whereby it is readily removable to permit a change in hoppers when a change in the style of fastener used is desired, thus obviating the necessity of emptying and refilling the hopper.

Another object of the invention is to provide an improved mechanism for segregating fasteners from the mass in the hopper and delivering them singly to a raceway for delivery to the inserting devices.

With these objects in view that feature of the invention which relates to the improved means for mounting the hopper to insure ready removability, contemplates the provision of a friction clutch on the hopper shaft between the fastener segregating devices within the hopper and their actuating means on the machine frame, means for dis-

connecting the clutch from the hopper, and a bayonet joint connection between the hopper and its support.

That feature of the invention which relates to the improved mechanism for segregating fasteners contemplates the provision of a picker plate having a plurality of fastener-lifting arms, and mechanism for imparting an intermittent rotary motion thereto which prevents overthrow of the picker arms and invariably places them, in succession, in proper position to deliver their fasteners to the raceway.

Although the features of invention just described are in their illustrated embodiment applied to a machine for inserting fasteners simultaneously in two superimposed sheets of material, these features of the invention, as defined by the claims, are not limited in their application to this type of machine but are equally applicable to a machine for inserting fasteners in a single sheet of material.

The preferred embodiment of the invention is illustrated in the accompanying drawings, in which—

Figure 1 is a front elevation of the hook hopper, the cover plate being partly broken away to show the interior mechanism; Fig. 2 is a vertical section on the line 2—2 of Fig. 1; Fig. 3 is a horizontal section on the line 3—3 of Fig. 1; and Fig. 4 is a detail, in elevation, of the driving mechanism for the picker plates within the hopper.

In the embodiment of the invention illustrated in the drawings, two raceways for delivering lacing hooks to the hook setting mechanism are shown, each of which consists of a plate 220 secured at its upper end to the upper end of the hopper supporting bracket E which is secured to the main frame of the machine. As the hooks are delivered from the hopper and pass down the plates 220 by force of gravity, they are held upon said plates by guard plates 224 arranged at right angles to the plates 220 and separated therefrom a sufficient distance to form slots to receive the necks of the hooks. The guard plates 224 are also secured at their upper ends to the bracket E.

The hopper for containing the lacing hooks is of such shape that two streams of

lacing hooks may be delivered simultaneously. The hopper is best shown in Figs. 2 and 3 and comprises side plates 234 and a circular shell 236 which is V-shaped in cross section, thus causing the hooks within the hopper to fall to each side into the path of the hook delivering mechanism which is located within the hopper adjacent the side plates. The hopper is removably supported upon the brackets D and E secured to the main frame in a manner presently to be described in detail. The raceway plates 220 abut against the hopper just inside of its side plates and opposite slots (Fig. 3) within which the hook delivering picker plates 238 (Fig. 1) operate. These picker plates are of the usual well known construction and are driven intermittently by a mechanism now to be described.

Each picker plate is provided with a hub 240 (Fig. 2) which is secured to a shaft 242 journaled at its outer end in a bearing in the front side plate 234 and having at its inner end a disk 244 projecting through an opening in the rear side plate 234 and forming one member of a friction driving clutch. The other member of the friction clutch is formed by a second disk 246 (Figs. 2 and 4) which is secured centrally to a radially slotted wheel 248 mounted upon the hollow hub 250 of the disk 246 having a bearing in a casing 252 carried by the bracket D. The disks 244 and 246 forming the friction clutch are held in contact by means of a pin 254 (Fig. 2), provided with a hand wheel 256 and threaded into the hopper shaft 242 after passing through the hollow shaft 250. With this construction when the disks of the clutch are in engagement, the hopper shaft 242 and hollow shaft 250 form substantially one shaft which rotates in the journals formed in the forward wall 234 of the hopper and the rear wall of the casing 252. The casing 252, below the radially slotted wheel 248, is provided with a short shaft 258 (Figs. 2 and 4) which carries at its forward end a crank arm 260 having a tooth 261 adapted to enter the slots of the wheel 248 in succession as the shaft 258 is rotated. The wheel 248 is also provided with a succession of concavities around its periphery which are adapted to be engaged successively by the convexly curved surface of a disk 259 on the hub of the crank 260 and lock the shaft 242 against rotation during the time that the pin 261 is disengaged from the radial slots in the wheel 248 (see Fig. 4). This mechanism is similar to what is known as the "Geneva stop motion" but it is different therefrom in that the actuator 260 and the convexly curved locking surface formed on its hub are in different planes. This construction permits the convexly curved locking surface carried by the actuator to extend angularly for more than 180° and, there-

fore, to insure a rigid locking of the shaft 242 against rotation during the period of time that the pin 261 is disengaged from the radial slots of the wheel 248. Where the complementary curved locking surfaces are less than 180° in angular extent, the locking action is overcome before the radially slotted wheel is again engaged by its actuator and, therefore, there is an opportunity for the parts which are being held stationary, in this case the picker plates, to move and destroy their alinement with the raceways. The extended locking surface provided by the construction shown in Fig. 4 holds the picker arms successively at the ends of the raceways in a proper position for hooks to be delivered therefrom to the raceways during the entire time that the crank arm 260 is disengaged from the radial slots in the wheel 248.

The crank 260 is rotated continuously by the engagement of a worm gear 262 (Fig. 4), upon a shaft 264, with a second worm gear 266 (Fig. 2) threaded upon the hub of the crank. The shaft 264 is journaled in bearings formed therefor in the hopper supporting bracket E and other suitable bearings on the main frame, and is rotated by connections to the main shaft of the machine, all as shown in the co-pending application hereinbefore referred to. So long as the shaft 264 rotates the picker plates will be continuously supplying lacing hooks to the raceways.

As hereinbefore mentioned, it is desired at times to either change the size or style or possibly the color of lacing hook upon which the machine is to operate, and instead of resorting to the slow process of removing all the loose lacing hooks from the hopper which is in the machine and then re-supplying that hopper with other lacing hooks of the kind or color desired, in the present machine the hopper is so mounted that it can at such times be readily and quickly removed and another substituted therefor. To this end the hopper is held to its support by means of bayonet joint and swing bolt and nut and slot connections, now to be described. Referring first to Figs. 1 and 3, the upper end of the bracket E has pivoted thereto a swinging bolt 280 which is adapted to enter a slot 282 formed in a lug (Fig. 2) projecting from the left hand lower quadrant of the hopper. After being swung in place in said slot, the hopper and bracket are drawn together by means of a nut 284 threaded on the bolt.

Referring now to Figs. 3 and 4, the rear wall of the hopper is provided with a series of, in the present instance three, L-shaped lugs 286 which, with their outer faces, bear against the inner surfaces of guideways 288 (Fig. 4) formed at the periphery of the casing 252. To secure the hopper in locked

position its lugs 286 are first placed in contact with the guideways 288, and then upon a rotation to the left (Fig. 4) the lugs are guided by the guideways so that they invariably move beneath the projecting hooks 290 formed on the guideways, which act to hold the hopper securely from moving outwardly from the casing 252. This is in effect a bayonet joint and its advantages will be clear, as the guideways 288 enable the hopper to instantly be placed for its rotary movement into locked position. With a hopper mounted in this manner, in order to remove it from the machine it is merely necessary to first unscrew the pin 254 until it is free of the shaft 242 and the friction clutch formed by the disks 244 and 246 is thus disengaged, and then swing the bolt 280 out of its engagement with the slot 282 in the lug on the hopper, and finally give the hopper an angular bodily movement about the shaft 242 as an axis until the L-shaped lugs 286 are free of the hooks 290. After these operations the hopper may be pulled forward from the bracket D and taken from the machine. A new hopper may be quickly placed in operative position by a reversal of the operations just described.

Obviously changes may be made in the form, character and the relation of the parts within the scope of the invention, the characterizing features of which are set forth in the claims by the intentional use of generic terms and expressions inclusive of various modifications.

What is claimed as new is:—

1. A machine for inserting fasteners, having, in combination, a hopper, fastener supplying devices within the hopper, a hopper supporting bracket, actuating means for said devices also supported by the bracket, means for disconnecting the fastener supplying devices from their actuating means, and means connecting the hopper with its bracket, permitting removal of the hopper, after such disconnection, by an angular bodily movement thereof, substantially as described.

2. A machine for inserting fasteners, having, in combination, a hopper, a raceway leading therefrom, a hopper supporting bracket, a raceway supporting bracket, a bayonet joint connection between the hopper and its bracket, and a swing bolt and nut and slot connection between the hopper and raceway bracket, substantially as described.

3. A machine for inserting fasteners, having, in combination, a hopper, a shaft within the hopper, rotary fastener supplying devices mounted on said shaft, a hopper supporting bracket, means for rotating the hopper shaft including a friction clutch having one member supported by the shaft and one member supported by the bracket, remov-

able means connecting the bracket-supported clutch member with the shaft-supported clutch member, and a bayonet joint connection between the hopper and its bracket, substantially as described.

4. A machine for inserting fasteners, having, in combination, a hopper, a raceway leading therefrom, a picker plate mounted on a shaft in the hopper having a plurality of fastener-lifting arms, and means for rotating the picker plate intermittently to bring the lifting arms successively into position to deliver fasteners to the raceway, comprising a radially slotted wheel connected to the shaft, a crank arm having a tooth to enter said slots in succession, complementary curved surfaces on the perimeters of the wheel and crank hub to lock the shaft against movement when the crank is disengaged from the wheel, and means to rotate the crank arm continuously, substantially as described.

5. A machine for inserting fasteners, having, in combination, a hopper, a raceway leading therefrom, a picker plate mounted on a shaft in the hopper having a plurality of fastener-lifting arms, and means for rotating the picker plate intermittently to bring the lifting arms successively into position to deliver fasteners to the raceway, comprising a radially slotted wheel connected to the shaft, a crank arm arranged beside and overlapping the wheel having a laterally projecting tooth to enter said slots in succession, complementary curved surfaces arranged in the same plane on the perimeters of the wheel and crank hub to lock the shaft against movement when the crank is disengaged from the wheel, and means to rotate the crank arm continuously, substantially as described.

6. A machine for inserting fasteners, having, in combination, a hopper, a raceway leading therefrom, rotary devices within the hopper to deliver fasteners to the raceway, a rotary shaft to actuate said devices, a clutch connecting said shaft and devices, and means within the shaft and acting in the axis of said shaft to disconnect said clutch, substantially as described.

7. A machine for inserting fasteners, having, in combination, a hopper, a raceway leading therefrom, rotary devices within the hopper to deliver fasteners to the raceway, a rotary shaft, means to impart a step-by-step rotation to said shaft, a clutch connection between said shaft and devices comprising two friction disks, one connected to the shaft, and one connected to said devices, and means under control of the operator for disconnecting the clutch, substantially as described.

8. A machine for inserting fasteners, having, in combination, a hopper, fastener supplying devices within the hopper, a hopper

supporting bracket, actuating means for said devices also supported by the bracket, means for disconnecting the fastener supplying devices from their actuating means, and means connecting the hopper with its bracket comprising lugs on the hopper, hooks on the bracket and guideways for locating the lugs in position to be guided beneath the hooks on an angular bodily move-

ment of the hopper, substantially as described.

In testimony whereof I have signed my name to this specification in the presence of two subscribing witnesses.

GEORGE GODDU.
